ELECTRIC DISCHARGE DEVICE

Joseph A. Wainwright, Syracuse, N. Y., assignor
to General Electric Company, a corporation of
New York

Application July 2, 1946, Serial No. 680,895

7 Claims. (Cl. 250—157)

1

My invention relates to electric discharge devices of the beam type and particularly to improved beam controlling structures for devices of this type.

It is well known that the electron beam of a cathode ray tube includes charged bodies other than electrons. For example, the beam usually contains negative ions in appreciable quantities which tend to form a black spot on the fluorescent screen of the tube. It is also known that particles having different charge-to-mass ratios are deflected different amounts by a magnetic field but are substantially uniformly deflected by an electric field. Cathode ray tubes have been provided with means for selectively deflecting the electrons and ions by means of suitable electric and magnetic fields. In accordance with an important aspect of my present invention I provide a new and improved discharge device of the beam type in which the ions are removed from the beam by the selective deflection of the ions and electrons.

It is an object of my invention to provide a new and improved electric discharge device of the beam type.

It is another object of my invention to provide improved beam deflecting means for an electric discharge device of the beam type which selectively deflects the ions and electrons in the beam.

It is a still further object of my invention to provide a new and improved structure for providing a transverse magnetic field for controlling the beam of an electric discharge device.

Further objects and advantages of my invention will become apparent as the following description proceeds, reference being had to the accompanying drawing, and its scope will be pointed out in the appended claims. In the drawing, Fig. 1 is an elevational view, partly in section, of a cathode ray tube embodying my invention; Fig. 2 is an enlarged sectional view of a portion of the device illustrated in Fig. 1 and showing in detail the electron gun structure, and Fig. 3 is a sectional view taken along the line 3—3 of Fig. 2.

Referring now to the drawing, I have shown my invention as applied to a cathode ray tube which may be of the type employed in television receivers, and which includes an envelope 1 formed of glass. The envelope may be of the usual shape including an elongated neck portion and an enlarged or bulbous portion closed at its outer end to provide a viewing window of the tube. The inner surface of the window is provided with a fluorescent coating 2 which may be applied in accordance with techniques well understood in

the art and which may to advantage include what are commonly known as medium persistent phosphors. The gun structure is adjacent the neck portion of the envelope and is supported from the end wall by a plurality of conductors 3 which are sealed through the envelope wall. The gun includes a generally cylindrical cathode 4 supported centrally within a grid member 5 which is in the form of an inverted metallic cup having an aperture 6 in alignment with the emitting surface of the cathode. As illustrated, the cathode is supported within the grid cylinder 6 on an insulating disk 7 and is positioned and retained by suitable spacing and retaining washers 8, 9 and 10. The grid 5 is supported on a flanged collar 11 which is in turn secured to the supporting conductors 3. In accordance with usual electron gun construction, a plurality of glass supports or stalks 12 are secured to the grid cylinder 5 by laterally projecting metal lugs 13. A second or accelerating grid cylinder 14 and an anode cylinder 15 are supported in axial alignment with the grid cylinder 5 and in spaced and insulated relation with respect thereto by a plurality of lugs 16 which are sealed into the supporting stalks 12. As illustrated, the outer end of the anode cylinder 15 is closed by a disklike member 17, the outer edge of which is spaced slightly from the wall of the envelope and which is provided with a centrally located limiting aperture 18 which confines the electron beam projected from the gun. The outer edge of the gun is physically positioned in the central portion of the neck by a plurality of spring fingers 19 which extend along the envelope wall and contact the interior conducting coating 20 which is applied to the inner wall of the envelope from the central portion of the neck to within approximately one inch of the fluorescent screen 2. The conducting coating may be formed of a graphite solution in accordance with well known practices, and serves as a return conducting path for electrons liberated from the fluorescent screen 2.

As illustrated in the drawing, the outer end of the grid cylinder 14 and the inner end of the anode cylinder 15 are positioned in mutually spaced and insulated relation and shaped to define a gap extending at an acute angle with respect to the longitudinal axis of the gun. Since the anode cylinder 15 operates at a high positive potential with respect to the grid cylinder 14, it will be apparent that the electric field existing across the gap will deflect the electrons of the beam to the left, as viewed in Fig. 2.

The various parts of the electron gun are elec-

trically connected with terminal prongs 21 carried by an insulating base 21' by suitable lead-in conductors 22. The base is secured to the end of the neck portion of the envelope by a body of cement 23. An anode or high voltage terminal 24 is provided on the side wall of the bulbous portion of the envelope 1 and a conductor 25 sealed through the envelope wall connects the terminal with the internal conducting coating 20. An exterior coating 26 of conducting material may be applied to the outside of the envelope and in cooperation with the internal coating 20 provides a capacitive anode connection.

In accordance with an important aspect of my invention, I provide an improved structure for providing a pair of transverse magnetic fields on opposite sides of the gap between cylinders 14 and 15 and which in conjunction with the deflection provided by the electrostatic field across the gap between grid 14 and anode 15 effect the selective deflection of the electrons and ions of the electron beam. As illustrated in the drawing, a pair of permanently magnetized spring rings 27 and 28 are positioned on the neck of the envelope on opposite sides of the gap between the accelerating grid cylinder 14 and the anode cylinder 15. These rings may to advantage be formed of one of the copper-nickel-iron alloys which provides a magnet of light weight and high coercive force. The rings are resilient and are easily mounted on the neck of the tube. As illustrated, the rings 27 and 28 are split and mounted on a resilient support which in the illustrated embodiment takes the form of a rubber tube 29 surrounding the neck of the envelope. With this construction, it is possible to adjust the angular positions of the rings to provide the desired control of the beam. The rings 27 and 28 are magnetized in such a manner that a north pole exists at a restricted circumferential portion of the ring and a south pole is provided at a diametrically opposite region. The rings 27 and 28 are further positioned or displaced rotationally 180°; that is, the north pole of one magnet occupies the same radial plane as the south pole of the other magnet.

In order to assist in concentrating the transverse magnetic field in the region just beyond the aperture of the accelerating grid, a pair of identical pole pieces are provided on opposite sides of the grid cylinder 14. As illustrated in the drawing, each pole structure includes an angular member having one arm 30 extending longitudinally of the gun structure and the other arm extending radially and secured to the outer wall of the accelerating grid by a suitable tab 31 which is welded to the pole piece and to the grid cylinder. Since rotation of the ring 27 displaces the poles thereof with respect to the pole pieces it changes the strength of the field acting on the electron beam. By independent rotation of rings 27 and 28 the desired trapping of the ions is effected and the beam of electrons is directed to the desired spot on the screen.

The manner in which the electric field produced between the adjacent ends of cylinders 13 and 14 and the magnetic fields produced by the permanent magnets 27 and 28 operate to deflect the electron beam and to separate the electrons and ions will be more apparent from a consideration of the following description of the operation of the device. As will be readily appreciated, the accelerating grid cylinder 14 is operated at a positive potential with respect to the grid cylinder 5 and the anode cylinder 15 has a positive

potential with respect to the grid cylinder 14. Electrons emitted from the active surface of the cathode 4 pass through the aperture 6 of the control grid and through the aperture of the accelerating grid into the region beneath the pole pieces 30. The permanent magnet ring 27 is positioned on the neck of the envelope with the north pole opposite the pole piece shown in Fig. 2; that is, the pole piece at the back of the electron gun. In other words, the magnetic field lines of force project from the plane of the paper in a direction perpendicular to the axis of the electron gun. With the magnetic field in this direction, the electrons and ions of the beam are deflected to the right, as viewed in Fig. 2. As stated earlier in the specification, the deflection of the charged particles in the magnetic field is dependent upon the charge-to-mass ratios of these particles so that the ions of the beam are deflected substantially less than the electrons of the beam. As the beam passes the gap between the adjacent ends of the accelerating grid cylinder 14 and the anode cylinder 15, the beam is deflected to the left, as viewed in Fig. 2. The deflection of the heavy ions at this point is substantially the same as the deflection of the electrons, but since the ions were substantially undeflected by the magnetic field, they are now directed to the left of the axis of the electron gun and are collected on the wall of the anode cylinder 15. The electrons are deflected to the left substantially to the center of the anode cylinder and pass through the limiting aperture 18 at the outer end of the anode cylinder. The effect of the electric and magnetic fields has been described above as if they were acting independently, actually the electrons and ions are deflected in accordance with the resultant effect of these two fields. The second permanent magnet ring 28 is mounted with the north pole on the top of the envelope, as viewed in Figs. 1 and 2, and is effective to deflect the electrons to the right. The use of the second magnet ring, which is preferably much weaker than the magnet ring 27 provides an adjustment for bringing the electron beam exactly into the center of the anode cylinder 15. It is apparent that by adjusting the angular position of the ring 28 independently of the ring 27 that the final position of the electron beam may be controlled. It is also apparent that certain structural features of the magnet structure may be employed for purposes other than as components of an ion trap.

While I have shown and described a particular embodiment of my invention, it will be obvious to those skilled in the art that changes and modifications may be made without departing from my invention in its broader aspects, and I therefore aim in the appended claims to cover all such changes and modifications as fall within the true spirit and scope of my invention.

What I claim as new and desire to secure by Letters Patent of the United States, is:

1. In combination, an electric discharge device of the beam type including an envelope, a source of electrons including an electron gun positioned at one end of said envelope, means including said gun for producing a beam of electrons and subjecting said beam to an electrostatic field having a component transverse to the axis of said beam, and means for subjecting said beam to a transverse magnetic field to deflect the electrons of said beam in a direction opposite to the deflection produced by said electrostatic field, said last mentioned means including a substantially com-

plete ring of permanently magnetized material magnetized to produce a flux in the direction of a diameter of said ring resiliently supported on the exterior of said envelope.

2. In combination, an electric discharge device of the beam type including an envelope, a source of electrons including an electron gun positioned at one end of said envelope, means including said gun for producing a beam of electrons, and means for subjecting said beam to a transverse magnetic field to deflect the electrons of said beam in a direction transverse to the axis of said beam, said last mentioned means including a substantially complete ring of permanently magnetized and mechanically resilient material supported on the exterior of said envelope.

3. In combination, an electric discharge device including an envelope having an elongated neck portion, an electron gun structure supported within said envelope for producing an electron beam, and means for controlling the transverse position of said beam including a permanently magnetized substantially complete spring ring supported on the exterior of said neck portion and rotatably and axially adjustable to control the magnitude and direction of the deflection of said beam produced by said means.

4. In combination, an electric discharge device including an envelope having an elongated neck portion, and electron gun structure supported within said envelope for producing an electron beam, a layer of resilient material surrounding said neck portion, and means for controlling the transverse position of said beam including a permanently magnetized substantially complete spring ring supported on said material and adjustable in position relative to said material to control the magnitude and direction of the deflection of said beam produced by said means.

5. In combination, an electric discharge device of the beam type including an envelope having a neck portion, an electron gun supported in said neck portion and including adjacent conducting members supported in spaced insulated relation and adapted when energized by potentials of different magnitudes to subject the electrons of said beam to a transverse electric field, and permanently magnetized ringlike members supported on the neck portion of said envelope in axially spaced relation on opposite sides of the space between said conducting members.

6. In combination, an electric discharge device of the beam type including an envelope having a neck portion, an electron gun supported in said

neck portion and including adjacent conducting members supported in spaced insulated relation and adapted when energized by potentials of different magnitudes to subject the electrons of the beam to a transverse electric field, a pair of ring-like members of permanently magnetized material supported in axially spaced relation on the neck portion of said discharge device, said rings extending substantially completely around said neck portion and being magnetized to produce a flux along a diameter of the rings, and means for supporting said rings permitting rotational adjustment of one of said rings relative to the other, the resultant action of said rings and the electric field produced by said members cooperating to separate the ions and electrons of the beam.

7. An electric discharge device of the beam type including an envelope having a neck portion, an electron gun supported in the neck portion of said envelope providing an electron beam, said gun structure including generally cylindrical grid and anode electrodes supported in mutually spaced end-to-end relation, the adjacent ends of said electrodes defining a gap therebetween extending at an acute angle with respect to the axis of said beam, a pair of ring-like permanent magnets supported on said neck portion at points spaced along said beam and on opposite sides of said gap, said magnets being similarly magnetized and rotationally displaced 180 degrees to provide transverse magnetic fields of opposite polarity on opposite sides of said gap and cooperating with the electric field produced across said gap to selectively deflect the electrons and ions of said beam and to cause the collection of the ions on said anode electrode.
